UNITED STATES PATENT OFFICE.

ALFRED P. LEE, OF PHILADELPHIA, PENNSYLVANIA, ASSIGNOR TO JAMES W. IVORY, OF PHILADELPHIA, PENNSYLVANIA.

APPLIANCE FOR MAKING DENTAL CASTINGS.

No. 920,483.

Specification of Letters Patent.

Patented May 4, 1909.

Application filed June 16, 1908. Serial No. 438,739.

To all whom it may concern:

Be it known that I, ALFRED P. LEE, a citizen of the United States, residing in the city and county of Philadelphia, State of Pennsylvania, have invented a new and useful Appliance for Making Dental Castings, of which the following is a specification.

My invention relates to an appliance for making dental-castings such as inlays, 10 crowns, bridges, etc., and consists of novel means for reproducing an impression of a cavity in a tooth or other dental requirement from fused gold or other metal subjected to pressure of automatically created gas or 15 vapor, so as to completely fill the mold and be compressed therein, and for directing said gas or vapor after use from the chamber containing the same into the atmosphere.

It also consists of a novel device for forming a chamber in the moldene employed.

For the purpose of explaining my invention, the accompanying drawing illustrates a satisfactory reduction of the same to practice, but the important instrumentalities thereof may be varied, and so it is to 25 be understood that the invention is not limited to the specific arrangement and organization shown and described.

Figure 1 represents a perspective view of 30 an appliance for dental castings embodying the invention. Fig. 2 represents a partial side elevation and partial vertical section thereof. Fig. 3 represents a perspective view of the investment base and one of the 35 flasks employed. Fig. 4 represents a vertical section of a portion of the investment base on an enlarged scale, including attachments. Fig. 5 represents a vertical section of the flask, portion of the investment base, 40 and appliances. Fig. 6 represents a vertical section of the flask after removal from the investment base. Fig. 7 represents a vertical section of a former employed for producing a chamber in the moldene. Fig. 8 represents a section of the impression of a cavity 45 and the gate pattern pin impaled thereon. Fig. 9 represents a perspective view of the moldene-former shown in Fig. 7. Fig. 10 represents a side elevation of the product. 50 Similar letters of reference indicate corresponding parts in the figures.

Referring to the drawing:—A designates a base, in which is the cavity B, which is occupied by the pad C of asbestos or other 55 suitable material. Superimposed on said

pad and inclosed by the wall of said cavity is the ring D, in which are perforations E, which form air vents for a purpose to be hereinafter described.

Rising from the base A, are the ears F, on 60 which is mounted the lever G, depending from which is the inverted cup H, which is adapted to receive and hold a body of moldene, as at J, which is formed of clay, glycerin and other material, and having in 65 its underside the chamber K, which, in the present case, is produced by the former L, whose top M is convex and which may be contained in the casing N, the latter being adapted to be placed on the pad C and set 70 true within the ring D, after which the lever G is lowered, whereby the moldene is 75 pressed against the top of the former, thus compressing said material and forming chamber K therein.

P designates an investment-stand, on which are supported the conical patterns Q, which are fixed thereto and have vertical openings R centrally therein to receive the gate-pattern-pins S, which are removable 80 therefrom and have points T on their upper ends and shoulders U below the same.

V designates a flask, which is open at top and bottom and adapted to be placed on the stand P, as in Fig. 3, and subsequently on 85 the base A, as in Figs. 1 and 2, as will be hereinafter more fully explained.

On the stand P are clips W, which are adapted to embrace the flask V and retain the same firmly and steadily in position on 90 the stand, while permitting the removal of the same therefrom.

Fig. 3 shows the stand as adapted for use with a plurality of flasks, but to the same I do not limit myself.

The horizontal diameter of the former L is that of the flask V, so that in producing the chamber K the top rim of the flask V will enter the cup H, and bear upwardly against the base of the moldene in the cup, 100 so that when the lever G is lowered, as in Fig. 2, the lower edge of said cup overlaps the upper edge of the flask and renders the chamber K air and gas tight, especially is this the case since the top of the former L 105 has a shoulder M' at the base of the convex top M, the contour of said shoulder being imparted to the base of the moldeae J in the cup H producing the recess J', so that the top rim of the flask V enters said recess, and 110

so producing the tight joint between the moldene and flask, as heretofore referred to.

The operation is as follows:—Wax or other suitable material is placed in the cavity 5 of the tooth, so as to produce an impression X thereof, the same then being removed by means of the pattern-pin S, which pierces the same limited by the shoulders, as in Fig. 8. Said pattern is then inserted in the opening R of the pattern Q, as in Fig. 4, and the flask V placed on the stand, thus inclosing 10 said impression and the upper portions of the pattern Q, S. An investment or investment material Y is now poured into the flask, 15 thus covering said impression X, and portions of the patterns Q and pins S. When said material is set, it remains firmly in the flask owing to the pin or screw Y', which is passed through the wall of the flask into said 20 material, the flask then being carefully raised and removed from the stand P, when the pattern Q and pin S will remain on the latter, while the impression X is contained 25 in the investment Y, the place occupied by the pattern-pin S now producing in said investment the gate Z, and that occupied by the pattern Q producing the chamber Z' below said gate. The flask is now subjected 30 to heat, whereby the wax impression X will melt and flow out of the investment producing the die Z² in lieu thereof, as shown in Fig. 2. The hot flask is then inverted and placed 35 on the pad C, and retained true in position by the ring D, the lever G having been raised. A button V' of gold is now placed on the base 40 of the chamber Z', which is above, and subjected to a white heat, so as to fuse, whereby it may flow through the gate Z into the die Z², when the lever G is lowered tightly against 45 the top of the flask V, see Fig. 2. As the investment Y has become highly heated, a gas is generated therefrom. This mingles with that from the gold or metal, the gases occupying the tightly-closed chambers Z', 50 K, the expansion of which in said chambers exerting pressure on the fused metal, thus firmly forcing the latter into the die Z² and producing a casting V², in the present case that of an inlay, the same having therein a 55 neck V³, which is subsequently removed when the casting is inserted into the cavity of a tooth for further manipulation by the dentist. The gas in the chamber K, Z' gradually escapes into the atmosphere 60 through the investment Y and pad C, which are somewhat porous, and from the latter through the vents E in the ring D, which latter is superimposed on said pad, as previously stated. 65 It will be seen that the cup H is carried by the lever G as a plunger and movable therewith, the matrix-holder is disposed in the direction of the movement of the plunger and the cup carried thereby and constantly plastic non-porous material is within said cup.

If will be seen also that there is a one-piece mold having a hollow to receive the metal to be cast, a depression in the exterior surface of the mold which forms a crucible and a sprue-opening or gate directly connecting 70 the depression to the hollow, and furthermore that I employ materials having surfaces to provide mold and crucible cavities, the latter being directly connected by a sprue-opening or gate, said parts being so 75 constructed and related that molten metal may be forced directly from the crucible cavity into the mold cavity by a single action.

Having thus described my invention, what I claim as new and desire to secure by Letters 80 Patent, is:—

1. In an appliance of the character stated, a cup adapted to receive moldene, means for coöperation with said cup, including a flask, a yielding support for the flask, and means 85 for coöperation with said flask to close the upper end thereof.

2. In an appliance of the character stated, a cup adapted to receive moldene with a shoulder, a yielding pad, a flask adapted to 90 be supported upon said pad beneath said cup, and means embodying a perforated ring for closing the joint between said cup and flask rendering said chamber air and gas tight. 95

3. In an appliance of the character stated, a base, a pad on said base, a ring on said pad and having perforations, a lever mounted thereon, an inverted cup on said lever, and a flask, the latter being adapted to be supported on said base beneath said cup and to be closed at top by the same. 100

4. In an appliance of the character stated, an investment base, a flask adapted to be sustained thereon, and a perforated ring on 105 said base adapted to engage the side of said flask to hold the same in operative position.

5. In an appliance of the character stated, an investment base, a perforated ring, a pad supporting said ring, a flask adapted to be 110 supported thereon and receive an investment in said flask for forming a chamber and gate in the investment and leaving the shaped dental-impression in the latter.

6. In an appliance of the character stated, a flask which is open at top and bottom and adapted to contain an investment, a vent ring surrounding the lower end of the flask, means for supporting said flask, a cup receiving moldene and having depending portion 115 to embrace the upper end of the flask, and means adapted to be passed through the wall of said flask and enter the investment to control the latter from displacement.

7. In an appliance of the character stated, a base, a pad thereon, a perforated ring on said pad, and a flask adapted to rest on said pad within said ring. 125

8. In an appliance of the character stated, a flask, a gas chamber therein, and a gas- 130

discharging vent in communication with said chamber through the flask and opening into the atmosphere.

9. In an appliance of the character stated, a base, a pad, and a ring thereon, and a flask adapted to be supported on said pad with said ring, said ring having a vent therein adapted to discharge gas or vapor from said flask through said pad.
10. In a device of the class described com-

prising a plunger, a cup carried by the plunger and movable therewith, a matrix holder disposed in the direction of movement of the plunger and the cup carried thereby, and constantly plastic non-porous material within the cup.
